UNITED STATES PATENT OFFICE.

ERNEST SMITH WALKER, OF ST. JOHN, KANSAS, ASSIGNOR OF FORTY-NINE ONE-HUNDREDTHS TO CHARLES VAN FLEET, OF ST. JOHN, KANSAS.

RADIATOR.

Application filed March 29, 1922. Serial No. 547,885.

To all whom it may concern:

Be it known that I, ERNEST SMITH WALKER, citizen of the United States, residing at St. John, in the county of Stafford 5 and State of Kansas, have invented certain new and useful Improvements in Radiators, of which the following is a specification.

This invention relates to an improved radiator for internal combustion engines 10 and seeks, as one of its principal objects, to provide a radiator which will be formed of sections so that should any one of the sections become injured or otherwise damaged, the radiator may be readily re- 15 paired.

The invention has as a further object to provide a radiator embodying a plurality of core units or sections and wherein said units may be individually removed or replaced 20 so that the removal of one unit will not necessitate the displacement of any of the other units.

A still further object of the invention is to provide a radiator having top and bottom tanks and wherein the top tank may be removed.

Another object of the invention is to provide a radiator wherein the core units will be constructed to wedge between the top and bottom tanks so as to form tight joints therewith while slight displacement of the units, in the operation of removing said units, will serve to free the units with respect to said tank so that said units may 35 then be easily withdrawn.

And the invention has as a still further object to provide a radiator well adapted for use in connection with various prevalent makes of motor vehicle engines.

Other and incidental objects will appear hereinafter.

In the drawings:

Figure 1 is a front elevation of my improved radiator,

Figure 2 is a vertical sectional view on the line 2-2 of Figure 1, looking in the direction of the arrows,

Figure 3 is a horizontal sectional view on the line 3-3 of Figure 2, looking in the direction of the arrows,

Figure 4 is a perspective view of the radiator showing the core units removed and the top tank detached.

Figure 5 is a fragmentary detail sectional view particularly bringing out the manner

in which the top tank is connected with the radiator casing.

Figure 6 is a detail perspective view showing one of the emergency closure plates employed.

In carrying the invention into effect, I employ a casing including a bottom tank 10 having a top wall 11 and a bottom wall 12 extended upwardly at the ends of the tank to form supporting brackets 13 for the radiator, said brackets being designed for attachment to the side bars of a motor vehicle chassis frame for mounting the radiator upon the frame. The top wall 11 of the tank is provided with a plurality of 70 openings 14 therein and connected with the bottom wall is an outlet pipe 15. Rising from the tank at its extremities are side plates 16 reduced at their upper ends to form inwardly curved resilient tongues 17 and extending from said plates are side flanges 18. Fitting between said flanges are reinforcing strips 19 which are preferably 75 of wood although said strips may be formed of metal and overlying said strips are channel plates 20, the side flanges of which fit between the flanges 18 mating therewith. In the present instance, I have shown the casing of a size to accommodate a pair of the core units or sections employed and raising from the top wall of the bottom tank 10 medially thereof, is a vertical partition 21 for separating said units. However, as will be appreciated, the casing 80 may be enlarged to accommodate any 85 number of core units desired and, in such instance, a partition will be provided between each pair of the units. Detachably connected to the side plates 16 is a top tank 22 resting at its ends, as shown in detail in 90 Figure 5, upon the upper ends of the reinforcing strips 19. This top tank overhangs the bottom tank at its inner edge and is formed with an oval-shaped top wall 23 to which is secured a pair of spaced keepers 24 at each end of the tank. As best shown 95 in Figure 5, the tongues 17 of the side plates 16 are engaged through these keepers for 100 detachably securing the top tank in position, being curved longitudinally to lie flat against the curved top wall of the tank, and due to the resiliency of the tongues, said tongues will operate to clamp the top tank 105 against the upper ends of the reinforcing strips 19 so as to prevent rattling. Con- 110

nected to the inner end wall of the top tank is an inlet pipe 25 and rising from the top wall of the tank is a filler tube 26 normally closed by a cap 27. Mounted upon the tank at the bottom thereof is a bottom plate 28 forming a portion of the bottom wall of said tank and provided with a plurality of openings 29. As particularly shown in Figure 2, this plate is tapered from its rear edge toward its forward edge and is thus provided with a beveled lower face 30 inclining upwardly toward the outer side of the radiator, it being observed in this connection, that the top wall 11 of the bottom tank lies horizontally.

Removably fitting in the casing are core units or sections 31. These units may be of any approved type such, for instance, as the commonly known honey comb type, or may, as shown, include a plurality of vertically disposed tubes connected at their lower ends by a bottom plate 32 and at their upper ends by a top plate 33. Mounted upon said tubes are appropriate fins 34. Positioned between the bottom plates 32 of the units and the top wall 11 of the bottom tank 10 are, as shown in Figures 2 and 4, suitable gaskets 35 and positioned between the top plates 33 of the units and the plate 28 of the top tank are similar gaskets 36. These gaskets are all of like construction and attention is now directed to the fact that the top plates 33 of the units are tapered from their forward edges toward their rear edges and are accordingly formed with upper beveled faces 36 mating with the beveled face 30 of the plate 28. Accordingly, as each of the units is moved inwardly into the casing, said unit will wedge between the top and bottom tanks for compressing the gaskets 35 and 36 to form sealed joints between the units and said tanks firmly binding the units in position, the tubes of the units registering with the openings 14 and 29 of the top wall 11 of the bottom tank and the plate 28 of the top tank respectively when the units are in place. At the same time, the units may be readily withdrawn individually at the forward side of the casing and after said units have been shifted forwardly out of wedging engagement between the tanks, said units will be freed so that the units may be easily displaced. Formed in the rear margins of the top and bottom plates of said units are, as shown in Figure 3, slots 37 and extending through said slots are cap bolts 38 threaded into the wall 11 of the bottom tank and the plate 28 of the top tank for securing the

units at their rear sides. Extending through the forward margins of the plates 32 and 33 are cap bolts 39 also threaded into the wall 11 and plate 28 for securing the units at their forward sides. Thus, by loosening the bolts 38 and removing the bolts 39, the units may be withdrawn. I accordingly provide a construction whereby should one of the units of the radiator become damaged or otherwise impaired, such unit may be easily renewed without molesting the other units of the radiator.

Hingedly mounted upon the casing at its forward side is a screen 40 normally held closed by cap bolts 41 so as to provide protection for the core units at the front of the radiator and protecting said units at the rear of the radiator is a screen comprising a fixed section 42 upon which are mounted hinged sections 43 normally held closed by stud bolts 44 preferably carrying wing nuts, the section 42 being detachably secured in any approved manner upon the sides of the casing. It will accordingly be seen that I provide a radiator of particularly efficient construction and, as will now be appreciated, a radiator well adapted for a wide range of use.

In conjunction with the radiator casing, I provide emergency closure plates 45 which, as shown in detail in Figure 3, are provided at corresponding ends thereof with slots 46 to accommodate the bolts 38 and at their opposite ends with openings 47 to accommodate the bolts 39. Accordingly, if, in the practical use of the radiator upon a vehicle, one of the core units should become injured while upon the road where it would be impossible to repair the unit, such unit may be removed when a pair of the plates 45 may be employed to close the openings 14 and 29 in the top and bottom tanks exposed by the removal of said unit, the plates being clamped down against the exposed gaskets 35 and 36 forming sealed joints therewith.

Having thus described the invention, what is claimed as new is:—

An engine radiator including a bottom tank having side plates rising therefrom and provided with tongues, a top tank having keepers thereon accommodating said tongues, the tongues detachably connecting the top tank with said plates, and a core unit fitting between the tanks communicating therewith.

In testimony whereof I affix my signature.

ERNEST SMITH WALKER. [L. s.]
